UNITED STATES PATENT OFFICE.

LEONARD R. STEEL, OF CLEVELAND, OHIO.

MILK-CAN.

1,071,968.

Specification of Letters Patent.

Patented Sept. 2, 1913.

Application filed March 12, 1912. Serial No. 683,207.

To all whom it may concern:

Be it known that I, LEONARD R. STEEL, a citizen of the United States, residing at Cleveland, in the county of Cuyahoga and State of Ohio, have invented new and useful Improvements in Milk-Cans, of which the following is a specification.

This invention relates to milk cans and particularly to one including an outer metal jacket and an inner glass liner, the object of the invention being to provide a sanitary construction of a device of this kind which will permit of the convenient separation of the parts when it is desired to clean the same or replace worn or broken parts by new ones.

Another object of the invention is to provide a can which will include a sectional jacket and a liner, the latter being provided with means whereby it can be securely retained in the former during transit.

A still further object of the invention is to provide means for positively holding the liner against accidental displacement from the can when the cover section of the latter is removed and the can placed in a position to permit the contents of the liner to be poured therefrom.

Another object of the invention is to provide a can which will include relatively adjustable sections and means for holding the sections positively against separation in transit.

Another object of the invention is to provide cushioning means in the jacket to serve as a protecting agent to prevent the breakage of the liner.

In the drawings, forming a portion of this specification and in which like numerals of reference indicate similar parts in the several views:—Figure 1 is a side elevation of the can. Fig. 2 is a vertical section therethrough. Fig. 3 is a section on line 3—3 of Fig. 2 with parts omitted. Fig. 4 is a section on line 4—4 of Fig. 2. Fig. 5 is a horizontal section on line 5—5 of Fig. 2. Fig. 6 is a perspective view of one of the handles. Fig. 7 is a section on line 7—7 of Fig. 2. Fig. 8 is a vertical section through the clamping members of the can sections showing the means for preventing the relative rotation of the sections.

The can comprises a jacket 1 which includes the lower section 2 and the upper section 3. The lower section 2 comprises the inner and outer walls 4 and 5 and the con-

necting spaced bottom portions 6 and 7, the latter being provided with a peripheral depending flange 8 which is riveted or otherwise secured to the outer walls 5, as at 9. 60 The rivets 9 are also preferably secured by the external reinforcing band 10. The bottom portion 6 is curved upwardly, at 11, being embraced by the inner walls 4 and secured thereto by the fastening devices 12. 65 The space between the bottom portions 6 and 7 and the side walls 4 and 5 is filled with cork or other suitable insulating material 13. The side walls 4 and 5 of the lower jacket section 2 are connected with each other 70 by a stepped annular cap 14.

The top or cover section 3 of the jacket comprises the inner wall 16, and the outer wall 17. These walls are spaced apart and they are preferably curved downwardly in 75 the direction of the walls 4 and 5 of the lower jacket section 2, being connected together at their lower ends by a stepped cap 18 which is designed to frictionally seat against the cap 14 on the lower jacket section so as to form between the section an efficient air tight joint. The inner wall 16 is provided with an integral crown 19 which is spaced from a similar integral crown 20 of the wall 17. The crown 20 has riveted or 85 otherwise suitably secured thereto a member 21 on which is formed an outwardly flared manipulating flange 22 whereby the top section 3 of the jacket can be readily removed from or applied to the lower section 2. 90

An inner glass liner 23 is mounted in the jacket 1, the sides of the liner being spaced from the walls 11 and 4 of the jacket by means of the radially disposed cushioning members 24 which extend inwardly from 95 the wall 4 as shown in Fig. 2 of the drawings. The liner is preferably constructed of glass, and as shown, it partly extends into the cover section 3 of the jacket, being provided preferably with a neck 25 which is exteriorly threaded, at 26, to removably receive the threaded cap 27. The cap is constructed of metal and secured thereto is a handle 28 whereby it can be freely rotated.

With a view of preventing detrimental 105 movements of the liner in the jacket during transit and with a further view of preventing the displacement of the liner from the lower section of the can when the latter is canted for the purpose of pouring the contents from the liner, I provide the means 29 which includes the attaching brackets 30

which are secured within the section 2 of the can adjacent to the upper end thereof. These brackets are provided with pivoted keepers 31 in which are formed upper eyes 32 to receive the hooked ends 33 of the fastening devices 34. The devices 34 are preferably snap hooks and each is provided at its upper end with an eye 35 which is pivotally mounted upon the retaining ring 36. The ring 36 is removably fitted upon the neck of the liner, being arranged in contact with the breast 37 of the liner so as to positively prevent movement of the latter in the jacket.

15 The lower section 2 of the jacket is provided with an exteriorly located angle ring 38 which is disposed immediately beneath a similar ring 39 on the upper section 3. The ring 38 is provided with an outwardly 20 extending horizontally disposed flange 40 which is arranged in parallel relation to the similar flange 41 on the ring 39. The ring 39 is provided with a suitable number of bayonet slots 42, the relatively narrow legs 25 43 of the slots being extended peripherally around the flange 41 as shown in Fig. 3 of the drawings. The lower ring 38 has its flange 40 provided with a series of upwardly 30 extending bolts 44 which are adapted to be extended through the bayonet slots 42 and to be disposed in the leg portions 43 of the slots on locking relative rotary adjustment of the jacket sections. The bolts are provided with winged clamping nuts 45 which 35 are adapted to engage against the flange 41 so as to hold the bolts operatively in their adjusted positions.

With a view of preventing retrograde movement of the top section of the jacket during transit, I provide said section with the locking pins 46. The flanges 40 and 41 are provided with alining passages 47 into which the pins 46 may be extended.

Handle members 48 are provided with leg 45 portions 49 which extend through the apertures 50 in the flange 40. These leg members are soldered, riveted or otherwise suit-

ably secured to the ring 38. The horizontal flange 41 on the top section 3 of the jacket is provided with relatively large recesses 50 51 through which the gripping portions of the handles extend, being disposed with relation to the walls of the top section of the jacket so as to permit the handles to be conveniently manipulated.

From the construction described it will be readily understood that the members 24 will positively prevent the lateral movement of the liner in the jacket while the means 29 will positively prevent the longitudinal 60 movement of the liner in the jacket, which acts effectively toward guarding against the breakage of the liner during transit of the can.

I claim:—

A can comprising superimposed separable sections, a liner removably mounted within said sections and supported upon the bottom of the lower section, brackets secured within the lower section and located 70 substantially in line with the upper edge thereof, the liner having a neck, a breast connecting the neck with the main body of the liner, keepers pivotally connected in the brackets and having eye portions extending 75 into the upper section of the jacket and disposed below the neck of the liner, a ring embracing the neck and resting against the breast of the liner, and bolts pivotally connected with the ring and adapted for detachable connection in the eyes of the keepers, whereby the ring may be removed from the liner and the keepers folded to extend away from the liner and to overlie the upper edge of the lower section of the can 85 when it is desired to remove the liner from the can or to insert the same therein.

In testimony whereof I affix my signature in presence of two witnesses.

LEONARD R. STEEL.
